UNITED STATES PATENT OFFICE

CLARENCE G. JOHNSON, OF DETROIT, MICHIGAN

GARAGE DOOR

Application filed October 6, 1924. Serial No. 741,837.

This invention relates to doors more particularly applicable for garages, and of the type known as flexible panel doors, wherein the door comprises a series of panels of substantial width arranged lengthwise and in marginal contact across a doorway, said panels being hinged together and adapted to be guided by suitable rails into an approximately horizontal position extending rearwardly from the proximity of the top of the doorway.

Several types of such door constructions have been already proposed and patented, and it is an object of the present invention to provide an improved construction of simple nature which may be readily applied as a unit to the doorways of garages or similar structures, and which when so applied will require a minimum of adjustment or particular care in the application, in order to effect a proper fitting of the door relative to the doorway.

It is also an object of the said invention to improve the construction of the hinging of the panels together, and at the same time to increase the scope of usefulness of the hinges, the invention being further directed towards the provision of combined hinges and brackets for the door, whereby both the positioning of the door when closed and the relative movement of the panels when the door is operated are controlled by the said hinges.

It is still further an object of the said invention to provide a very effective and simplified arrangement of door, brackets and track, in which contact of the door with the frame of the doorway is firmly established when the door is closed, and in which such contact is relieved in any other position of the door, in order to reduce friction or undesirable resistance to the opening or closing of said door.

Still further objects subsidiary to or resulting from the aforesaid objects, or from the construction or operation of the said invention as it may be carried into effect, will become apparent as the said invention is hereinafter further disclosed.

In carrying the said invention into effect I

may provide a unit comprising a sectional longitudinally panelled door having brackets extending rearwardly from the meeting edges of the panels and from the top and bottom of the upper and lower panel, the amount of rearward extension of the said brackets decreasing from the uppermost bracket to the lowermost bracket, certain of said brackets being in the form of special hinges, and all of said brackets having pintles arranged in a common plane at an angle to the face of said door when said door is in an upright closed position; rollers mounted on the said pintles with their axes lying in such common inclined plane; tracks having forward portions extending upwardly in said inclined plane and receiving said rollers, the upper parts of said tracks branching rearwardly from said forward parts, and forming approximately horizontal overhead tracks for said rollers when said door is opened; and supports for the said tracks whereby they are attachable to the garage or other structure with which the door is to be used. All of which is more particularly described and ascertained hereinafter, by way of example, having reference to the accompanying drawings, wherein

Figure 1 is a rear elevation of a door construction in accordance with the said invention, the upper parts of the tracks and supports being shown in section;

Figure 2 is a vertical transverse section of the said door;

Figure 3 is a horizontal section of the same taken on the line 3x—3x of Figure 2, and

Figure 4 is a fragmentary detail perspective view of one of the door hinges, together with its roller, and parts of the immediate construction associated therewith.

Similar characters of reference indicate similar parts in the several figures of the drawings.

1, 2 and 3 indicate the sides and top of the door frame of a garage, of which 4 is the front wall provided with beams 5 extending rearwardly from the upper inner side thereof; and 6, 7, 8 and 9 are the panels of the door adapted to be closed upon the rear faces of the door panel, these panels being of substan-

tial height, as will be apparent from the drawings as distinguished from the narrow strips such as are used in flexible doors commonly used for a great many years.

- 5 The panels are shown as having their meeting edges rabbetted in order to insure effectual interlocking thereof when the door is closed and on the marginal portions of the said door and on the back thereof, are arranged brackets of a type which will be further described. These brackets are generally indicated by the reference numerals 10, 11, 12, 13 and 14, and are provided with pintles 15, which pintles are arranged at progressively increasing distances from the door according to the height of the hinges from the bottom of the said door. Thus, the pintle of the bracket 14 is close to the door, whilst the pintle of the bracket 10 is positioned at a substantial distance rearwardly of the said door, and the pintle of the bracket 12 is at an intermediate distance; so that all of the said pintles lie in a common plane inclined to the vertical plane of the said door.
- 10 20 25 30 35 40 45 50 55 60 65 70 75 80 85 90 95 100 105 110 115 120 125
- 25 The brackets 11, 12 and 13 are in the form of special hinges and are shown as including arms 16 and 17 extending rearwardly from the door and having flanged extremities 18 and 19 which are secured to the rear surface of the said door by bolts 20, these arms in the case of the said hinges 11, 12 and 13 being each attached to adjacent panels, whereby the joints of the said panels extend between the said arms, and whereby the door may be flexed on its hinges and the panels parted at the said joints when the door is so flexed.
- 30 35 40 45 50 55 60 65 70 75 80 85 90 95 100 105 110 115 120 125
- 40 The brackets 10 and 14 do not function in precisely the same manner as the brackets 11, 12 and 13, inasmuch as they are not hinges in the same sense and may accordingly be of a non-flexible construction, such as is shown in the illustration of the bracket 14 which is simply in the form of an arm 21 having a base plate 22 secured to the lower part of the door.
- 45 50 55 60 65 70 75 80 85 90 95 100 105 110 115 120 125

is elevated from its fully closed position, thus practically eliminating friction between the door and the frame.

The said tracks 25 at the upper part of the front portions thereof are rearwardly curved at 26, branching into rearward extensions 27 forming overhead tracks within which the rollers may travel and be guided upon the raising of the door, and as the rollers travel through the curved portions of the tracks the door is flexed and the panels separated due to the extended nature of the hinges 11, 12 and 13, this action taking place between the panels successively as they travel upwardly; and the separation of the panels in this manner also results in a very easy action and elimination of any tendency to bind as the door is moved upwardly or downwardly to an open or a closed position.

By reason of the double rail construction a very positive positioning of the door is ensured at all times, whether open, partially open, or closed, without any tendency of the door to become displaced or out of alignment either with the rails or with the door frame when the door is closed, and the bracket arrangement of the hinges together with the wedge action described ensures an outward pressure upon the panels at the joints thereof, which is very desirable when the said door is closed, so that a very firm support of the door in its closed position is obtained, as will be readily understood.

Counterbalancing of the door may be secured, such as by means of suitably mounted spring controlled ropes 28. The tracks are provided with brackets 29, the uppermost of which may be associated with the beam 5 as part of the door unit, whereby the device may be supplied to buildings with which it is to be used as a complete unit, comprising a door, together with its hardware, tracks, supports and counterbalance devices ready for installation.

The operation of the door is very simple and may be very easily installed, the relative position of the forward parts of the tracks to the frame of the door being easily determined, and when so positioned, the balance of the mechanism requires no further adjustment in order to secure the correct fitting and efficient operation of the device.

The particular construction and number of the panels and brackets, and the form of the tracks, may be designed to suit various manufacturing requirements or conditions of operation, and the invention may be developed within the scope of the following claims, without departing from the essential features of the said invention, so that it is desired that the specification and drawings be read as merely illustrative and not in a limiting sense, except as necessitated by the prior art.

What I claim is:—

1. In a flexible panel door construction

adapted for the closing of a doorway, a plurality of horizontally hinged panels, brackets extending rearwardly of said door, certain of said brackets forming the hinges of said panels, and tracks guiding said brackets in an upward and then a rearward direction upon the opening of said door.

2. A flexible panel door construction according to claim 1, wherein the upwardly extending parts of said tracks are arranged in rearwardly inclined relation to the doorway, and the brackets are progressively increased in length according to their height on said door to secure a wedge action between said door and said doorway.

3. A flexible panel door construction according to claim 1, wherein the hinges include pintles having their axes arranged in a common plane inclined rearwardly from said door, and the upward parts of said tracks are correspondingly inclined, said pintles being provided with rollers engaging said tracks.

4. A flexible panel door construction according to claim 1, wherein the said hinges have extended bracket arms lying in a common plane each pair attached to adjacent panels.

5. In combination with the adjacent panels of a flexible door, hinges in the form of brackets having extended arms attached to contiguous parts of the adjacent panels and tracks guiding said brackets in an upward and then rearward direction upon the opening of said door, and pintles connecting said arms at a point in the same plane as the longitudinal plane of said tracks.

6. In combination with adjacent panels of a flexible door and tracks guiding said panels in an upward and then a rearward direction upon the opening of said door, hinges connecting said panels and having their members fulcrumed in a vertical plane spaced substantially rearward of the vertical plane of said panels whereby said joint is adapted to open upon the flexing of said door and being provided with rollers engaging said tracks.

7. In a door of the type described, in combination, tracks extending upwardly and then rearwardly, a flexible door comprising a plurality of panels of substantial width, hinges connecting said panels, said hinges including pintles, and rollers on said pintles, guided by said tracks, said pintles being situated substantially to the rear of said door whereby the panels of said door part when said door is flexed in travelling upwardly or downwardly over said track.

8. A door according to claim 7 wherein the tracks are inclined rearwardly from the normal closed position of said door and the relative distances of the pintles rearward of said door are correspondingly varied.

9. In a flexible panel door, a panel connecting hinge comprising a pair of spaced

apart arms secured to the contiguous parts of adjacent panels and extending angularly outwardly thereof to a desirable point spaced therefrom to form a fulcrum, and a pintle connecting said arms at said point.

10. In a flexible panel door, a supporting bracket in the form of a panel connecting hinge comprising a pair of spaced apart arms secured to the contiguous parts of adjacent panels and extending angularly outwardly thereof to a desirable point to form a fulcrum, a pintle connecting said arms at said point, and a roller carried by said pintle.

11. In a device according to claim 10, in combination, a double track including a pair of opposed rails between which said roller is engaged.

12. In a device according to claim 10, a double railed track engaged and guiding said roller, said track comprising a channel iron member having inwardly flanged edges forming the rails thereof.

13. In a flexible panel door construction adapted for the closing of a doorway, a plurality of horizontally hinged panels, brackets positioned on the rear face of said door, certain of said brackets forming the hinges of said panels, and tracks guiding said panels in an upward and rearward direction on the opening of said door.

14. A flexible panel door construction according to claim 1, wherein the hinges have pintles, the axes of which are arranged in the same plane as the longitudinal plane of said tracks, said pintles being provided with rollers engaging said tracks.

In testimony whereof I affix my signature.
CLARENCE G. JOHNSON.
